UNITED STATES PATENT OFFICE

LEON McNAMARA, OF ROCHELLE, ILLINOIS

FASTENING MECHANISM

Application filed March 12, 1928. Serial No. 261,012.

My invention relates broadly to a latch mechanism and more particularly to a window fastening means.

An object of my invention is to provide a means whereby a window may be securely fastened in either a closed or a partially opened position.

Another object of my invention is the provision of a device that will permit a window to be partially opened for the circulation of air and yet be securely fastened against intruders from without.

With the above and other objects in view the invention consists in the construction, combination and arrangement of parts as will be hereinafter more fully described.

Reference is to be had to the accompanying drawings forming a part of this specification in which like reference characters indicate corresponding parts throughout the several views, and in which

Figure 1 is a front elevation of my invention attached to a partially opened window.

Figure 2 is a section on the line 2—2 of Fig. 1,

Figure 3 is a detail fragmentary view showing my invention in a locked position on a closed window.

Figure 4 is a view on the line 4—4 of Fig. 3, and

Figure 5 is a fragmentary view of a portion of the latch arm of my invention.

Referring more particularly to the drawings, my invention consists of two parts, one of which, designated in its entirety by the numeral 5, is attached to the upper sash A of a window, and the other, 6, is attached to the lower sash B, and the two parts are so arranged on the respective sashes that they will be in horizontal alignment when the sashes are closed, as shown in Fig. 4.

The part 5 is composed of three members, a base or support 7, a pivoted latch arm 8, and a pin 9 connecting the base and latch arm and providing the pivot for the latter. The base member may be of any desired construction but of sufficient height that an opening provided therethrough for the reception of the pin will permit the latch arm to move freely without coming into contact with the

window sash. Suitable fastening elements 10 firmly secure the base to the sash. The latch arm member 8 is provided with a substantially longitudinally extending slot 11 that is slightly offset at one end, as at 12, and that terminates in a pocket 13, more clearly shown in Fig. 5, the purpose of which will be more fully explained hereinafter. The other end of the slot terminates in an enlarged opening 14. The pin 9 that connects the latch arm to the base is fastened securely to the arm at a point slightly offset from the vertical center line of the latch arm and is in vertical alignment with the pocket above referred to. It is freely rotatable and slideable within the opening through the base member and is prevented from becoming detached from the base during its movement by an enlarged shoulder 15.

The part 6 is secured to the other sash by any suitable means 16 and is provided with a stud 17 extending from approximately its center point towards the latch arm, which stud is provided with a collar 18. The collar is of such size that it will pass freely through the enlarged opening 14 but will be retained in the slot 11 and pocket 13, for purposes to be later explained.

As above stated my invention is designed to provide an effective window fastener when the window is in either a closed or a partially opened position. The method of accomplishing this purpose will now be explained. When the window is in a closed position the two sashes are in the position illustrated in Fig. 4, and the part 6, being so arranged with respect to the part 5 that the stud 17 lies in vertical alignment with the pin 9, the latch arm 8 will engage with the stud when it is turned to a horizontal position, as shown in Fig. 3. Due to the offset of the pin on the latch arm, a cam or eccentric action is imparted to the arm in its turning movement, thus producing a pressure on the stud. The arm in its engagement with the stud is seated between the body of the part 6 and the collar 18 on the stud. In the manufacture of the various parts consideration should be given to the various relative dimensions so that proper engagement of the latch arm

with the stud will be effected. If proper dimensions are provided, neither the upper sash can be lowered nor the lower sash raised when the parts are in the position just described. When it is desired to partially open the window for ventilation, as for instance during sleeping hours, the same parts will furnish an effective fastener for the window while so opened, permitting undisturbed 10 pose of the occupant of the room as he may retire free in mind that the window cannot be opened from without except by breaking or removing the glass to free the fastening mechanism. To so position and latch the 15 sashes together, the latch arm is removed from its horizontal fastening position to a vertical position, which frees the arm from the collar 18 allowing the arm 8 to be moved towards its base member to the position 20 shown in Fig. 4. The lower sash is then raised to the point where the stud registers with the enlarged opening 14 whereupon the latch arm is again moved from the base member to the position shown in Fig. 2. During 25 the continued raising of the lower sash the stud rides along the slot 11 until it finally lodges in the pocket 13, which being, as previously described, in vertical alignment with the pin 9, prevents accidental movement of 30 the arm 8 away from its vertical position. As the shoulder on the stud is larger in diameter than the slot is wide, these parts can be separated only at the enlarged opening, which requires that the sashes be brought into an 35 approximately closed position. It will thus be seen that although the window is open an effective fastener is provided. It will further be seen that my fastening mechanism permits the window to be opened at the top, 40 at the bottom, or both top and bottom and yet maintain the desired safeguard. The distance to which the window may be opened is limited only by the length of the slot in the latch arm, which should not be so great that 45 sufficient space is allowed through which an unauthorized person might crawl.

It will be understood that the above description and accompanying drawings comprehend only the general and preferred embodiment of my invention and that various minor changes in details of construction, proportion and arrangement of parts may be made within the scope of the appended claim and without sacrificing any of the advantages 55 of my invention.

Having described my invention, what I claim as new is:

In a fastening mechanism comprising in combination, a base member attached to a 60 slideable section, an arm pivotally carried by the base member, the pivot point of the arm being offset from the longitudinal center line of the arm, said arm being provided with a longitudinal slot having one end offset and 65 terminating in a pocket in longitudinal aline-

ment with the pivot point of the arm, and the other end terminating in an enlarged opening, a second member attached to an adjacent slideable section, and a stud carried thereby engageable by the arm in one of its positions and seatable in the pocket in another of its positions. 70
